UNITED STATES PATENT OFFICE.

ELMER L. SMITH, OF SPRINGFIELD, MASSACHUSETTS, ASSIGNOR TO PACKAGE MACHINERY COMPANY, OF SPRINGFIELD, MASSACHUSETTS, A CORPORATION OF MASSACHUSETTS.

LABEL-APPLYING MECHANISM.

Application filed November 4, 1921. Serial No. 512,900.

The present invention relates to label applying mechanism and is capable of being used to apply labels, stamps, or the like to articles of various characteristics.

The invention may be, and preferably is, so constructed as to be capable of application as an attachment to a machine for performing some other operation upon the articles such, for example, as wrapping them prior to the application of the labels thereto. As an attachment, the present invention is herein illustrated as embodied in a self-contained, compact mechanism adapted to be readily secured as a unit to the frame of a wrapping machine without the necessity of performing any machining operations or making any alterations or adjustments of operating parts other than the making of a single driving connection. The invention is not, however, restricted to use as an attachment but may if desired, be used independently of any other machine, and it is adaptable for applying labels, stamps, or the like, either gummed or unguammed, to the articles which may be wrapped or otherwise, as desired. In the event of the use of the invention as an independent machine, a suitable feed conveyer or the like may be arranged to operate intermittently and in a definite timed relation with the labeling mechanism for advancing the articles into position to be operated upon and for cooperating with the label affixing means to support an article while the label is being applied thereto.

In Letters Patent of the United States No. 1,306,359, granted June 10, 1919, to the present applicant, there is disclosed a stamp or label applying mechanism having means for affixing gummed stamps or labels to articles successively moved into its field of operations by intermittently actuated feed mechanism, and also means operative just prior to such application to moisten the face of the article which is to receive the stamp to enable the stamp to adhere thereto, the two elements being operable simultaneously on different articles during periods of rest of the latter at different stations. As set forth in said patent, the stamps are connected in a continuous strip which is supplied in the form of a roll and from which an individual stamp is severed just prior

to each stamp affixing operation. The stamp applying mechanism comprises a combined stamp-conveying nipper and stamp affixing plunger which oscillates periodically above the articles to be operated upon. At one end of its oscillatory stroke, the nipper is actuated to seize the free end of the stamp strip and as the nipper swings toward stamp affixing position it operates first to draw a portion of the strip of predetermined length across a member which operates to sever said portion to form a stamp. The stamp is then transferred by the nipper to the station where it is to be applied to one of the intermittently advancing articles. During the period of rest of said article at this station the stamp is released by the nipper and the stamp affixing plunger is actuated to depress the stamp into contact with the article, and inasmuch as this article was operated upon by the moistening device during the preceding period of rest of the feed means, the stamp will adhere to the article. Simultaneously with the stamp affixing operation, the moistening means operates at its station to moisten the upper face of the article immediately behind the one which has just been stamped.

One object of the present invention is to reorganize label or stamp applying mechanisms, of the general character above described and to improve the construction and mode of operation thereof for the purpose of enabling the entire action of the mechanism upon each article fed thereto to be performed at a single station and during a single period of rest in the feed of the article, thereby rendering such mechanism adaptable, without special adjustment of its parts, for cooperation with a wide variety of article feed devices.

In accordance with this object, one important feature of the invention consists in the provision, in a mechanism of the type referred to, of means for coating the labels or stamps during their transfer from the source of supply to the articles to which they are to be applied. By the above use of the term "coating" it is intended to cover broadly the application of an adhesive coating to unguammed labels the use of which is contemplated in the preferred embodiment of the invention herein illustrated, and also

the moistening of gummed labels, the employment of which is obviously within the scope of the invention.

A further object of the invention is to provide a mechanism of the character described having certain novel improvements in the construction and arrangement of its component parts tending to increase its efficiency and reliability in operation and to render it capable of operation at high speed.

A still further object of the invention is to provide, in mechanism of the character described, simplified and generally improved mechanical structure.

15 To the accomplishment of the above objects and such others as may hereinafter appear, the invention comprises the features of construction and combinations and arrangements of parts hereinafter described 20 and claimed, the advantages of which will be obvious to those skilled in the art.

The various features of the invention will best be understood from a description of the preferred embodiment thereof illustrated 25 in the accompanying drawings, in which:—

Fig. 1 is a side elevational view of the improved label applying mechanism, together with a small portion of a wrapping machine to which the label applying mechanism is applied as an attachment;

Fig. 2 is a view similar to Fig. 1, but on a reduced scale and showing a different position of the operating parts;

Fig. 3 is a top plan view of the mechanism shown in Fig. 2;

Fig. 4 is a plan view of a device for holding the end of the strip from which the labels are severed;

Fig. 5 is a fragmentary view of the strip 40 of labels; and

Fig. 6 is a plan view of the blade for severing the individual labels from the label strip.

Referring to the drawings, the invention 45 is therein shown as an attachment applied to a wrapping machine which may be of the type illustrated and described in the copending application of applicant and Horace J. Paynter, Serial No. 497,311, filed Aug. 31, 1921. The working parts of the present invention are mounted upon or supported by a single frame member 8 which may be rigidly secured in any suitable manner to one of the side frames 10 of the wrapping 55 machine. As shown, a screw 13 and a bolt 14 having a wing nut 15 threaded thereon, may be a sufficient means of attachment. Advantageously, the bolt 14 may extend through a vertical slot 16 in an ear 17 depending from the base of the frame 8, the slot being open at its lower end to facilitate the removal of the label applying mechanism.

60 The articles to be operated upon, one of 65 which is shown at 18 in Figs. 1 and 2, are

carried in peripheral pockets 20 in a rotatable drum 22. These articles have previously been wrapped and the wrapper ends are overlapped upon the upper face of the article in order that the wrapper may be sealed by the application of a stamp or label to said upper face. The drum 22 is actuated intermittently, by means fully described in said application, to successively feed the articles to a position of rest at the top of the drum where they are properly located and firmly supported to receive the stamp or label.

The present label applying mechanism, in common with that of the patented mechanism above referred to, is adapted to use labels or stamps in continuous strip form. Provision is made for receiving and guiding the label strip as it unwinds from a supply roll (not shown) which may be supported upon an arbor that is journaled in suitable bearings at any convenient point.

The label strip, indicated at 26, passes from the supply roll, over a flanged guiding roller 28 and thence through a friction device 30 which may be supported upon an arbor that is journaled in suitable bearings at any convenient point.

Both the guide roller 28 and the friction holding device 30 are carried by a bracket 32 which may be supported in any suitable manner. As shown, the bracket 32 is rigidly secured to a second bracket 34 which is screwed to a portion of the framework of the wrapping machine. If desired, however, the bracket 32 may be designed for attachment directly to the framework of the labeling mechanism itself.

As clearly illustrated in Fig. 5, the label strip is provided, at spaced intervals throughout its length, with transverse rows of perforations, after the manner of the usual coil of postage stamps, which divide the strip into a series of individual labels or stamps adapted to be separated along the rows of perforations. The present mechanism is designed to operate upon labels supplied thereto in an ungummed state, although obviously the mechanism may be modified to operate upon gummed labels without departing from the spirit of the invention.

The friction holding device 30, as shown in detail in Fig. 4, comprises a pivotally mounted presser member 38 which overlies the label strip and presses it downwardly against a supporting platform 40 formed integrally with the bracket 32. The presser member 38 is fixedly secured to a horizontal rock shaft 42 which is mounted in ears 44 rising from the platform 40 adjacent the opposite longitudinal edges of the label strip.

120 The friction holding device 30, as shown in detail in Fig. 4, comprises a pivotally mounted presser member 38 which overlies the label strip and presses it downwardly against a supporting platform 40 formed integrally with the bracket 32. The presser member 38 is fixedly secured to a horizontal rock shaft 42 which is mounted in ears 44 rising from the platform 40 adjacent the opposite longitudinal edges of the label strip.

The rock shaft 42 is acted upon by a spring 46 surrounding an extension of the shaft and arranged to hold the presser member in yielding engagement with the label strip. 5 The presser member 38 is provided with a tail 39 which may conveniently be depressed to facilitate the threading of the end of the strip through the holding device. The holding device 30 also functions to position the 10 free end of the label strip transversely relatively to the label transferring and affixing device 50 so that the label will be properly located upon the article when applied thereto. To this end, the upstanding ears 15 44 are provided with adjustable positioning members in the form of screws 48 which are threaded through said ears, the screws being arranged in axial alinement with each other and disposed in the horizontal plane of the 20 end portion of the label strip so that the inner ends of the screws will engage the opposite edges of the strip. The screws are readily adjustable to vary the position of the labels and suitable lock nuts 49 may be 25 provided for binding the screws in adjusted positions.

The operating parts of the label applying mechanism comprise, in general, the oscillatory label transferring and affixing device 30, already referred to, which is movable back and forth between the holding device 30 and the drum 22 and which functions to seize a label at the end of the supply strip, to transfer the label to a position above the 35 drum and to affix the label to the article carried in the upper pocket of the drum; an oscillatory knife 52 for severing an individual label from the supply strip prior to the transfer of the label to the drum; and an adhesive applying device including the glue roll 54, for coating the severed label during the transfer thereof.

The label transferring and affixing device 50 comprises a flat label affixing plate 58 and a movable nipper jaw or finger 60, which cooperates with one end portion of the plate 58 to seize a label and to hold it during its transfer from the holding device 30 to the drum 22. The portion of the plate 58 which cooperates with the nipper 60 is preferably bevelled, as shown in Fig. 1, to conform to the shape of the inwardly bent free extremity of the nipper jaw 60 and the bevelled portion of the plate 58 is offset sufficiently from the plane of the label affixing face of said plate to insure that the nipper will not engage the article while the label is being applied thereto. The label affixing plate 58 and the nipper jaw 60 are both mounted upon the lower portion of an arm 62 the upper portion of which is pivotally connected, by a horizontal stud 64, with a vertically oscillating carrier 66. To facilitate the setting up adjustment of the parts 65 the stud 64 is advantageously provided with an eccentric portion 65 which extends through a split sleeve on the carrier 66 and is adjustably secured therein by the usual binding screw 67. The carrier 66 is mounted to oscillate upon one end of a horizontal 70 sleeve 68 which extends through and is rigidly secured within a boss 70 (Fig. 3) on the framework 8. Axial displacement of the carrier 66 is prevented in one direction by the boss 70 and in the opposite direction 75 by a rocker member 72 the mounting and function of which will be hereinafter explained. The carrier 66 is oscillated to effect the transfer of the labels from the supply strip to the drum 22 by means of a crank 80 pin 74 projecting from the side of a disk 76 which is fixed to the front end of a horizontal main shaft 78. The crank pin 74 extends loosely through a slide block 80 which is adapted to reciprocate in a radial guide-way 82 on the carrier 66. It will be seen by reference to Fig. 3 that the travel of the crank pin 74 through that half of its orbit which is nearer the axis of oscillation of the carrier 66 takes place during the advance stroke of the carrier 85 and of the label affixing device 50 and consequently it will be obvious that the advance or operative stroke of the label affixing device will occur more rapidly than the idle 90 or return stroke thereof.

The main shaft 78 is journaled in a bearing upon the frame 8 and is adapted to be driven from the wrapping machine or other machine to which the labeling attachment is applied. To insure that the labeling mechanism shall be driven in a definite timed relation to the operating elements of the wrapping machine, provision is made for transmitting motion from the latter to the former by means of a sprocket chain and to this end a sprocket wheel 86 is rigidly secured to the rear end of the main shaft.

As the carrier 66 oscillates back and forth, the movement of the pivoted arm 62 is controlled by means of a cam 88 which is fixedly secured to a portion of the frame 8. The cam 88 has an inclined cam face which is engaged by a cam roll 90 carried by the arm 62 and held against the face of the cam by a spring 92 which is secured at one end to an upward extension of the arm 62 and at the other end to the carrier 66. The construction and arrangement of the cam 88 and the operating parts just described is such that when the carrier 66 is at the upper limit of its oscillatory movement the nipper 60 and the label affixing plate 58 are properly positioned to cooperate with each other for the purpose of seizing the free end of the label strip 26 which projects slightly beyond the holding device 30, as shown in Fig. 1. At the beginning of the downward movement of the carrier 66, the free end of the label strip is drawn

through the holding device 30 and stretched across the lower surface of the label affixing plate 58. When a portion of the strip of sufficient length to form a label has been drawn through the holding device 30, the knife 52 is actuated, as will hereinafter appear, to sever the label from the strip. As the carrier 66 continues its downward movement the label affixing plate 58 advances under the control of the cam 88 in such a manner that the leading end portion of the label carried by said plate is first brought into contact with the glue roll 54 along a line at right angles to its direction of movement. Thereafter, the cam roll 90 rides along a depressed portion 94 in the face of the cam 88, causing the arm 62 to swing relatively to the carrier 66 in such a manner that the label affixing plate is tilted so as to maintain a substantially tangential relation to the glue roll and to cause the line of contact between the roll and said plate to progress rearwardly until substantially the entire exposed surface of the label has been brought into contact with the glue roll 54. During the remainder of the downward movement of the carrier 66 and arm 62, the movement of the plate 58 is so controlled by the cam 88 that the label is finally brought into contact with the article by a movement substantially at right angles to the article. When the plate 58 reaches the limit of its movement it will lie in a horizontal plane parallel to the plane of the upper face of the article 18 and separated therefrom only by the thickness of the label carried thereby. Thus all portions of the coated face of the label will be brought simultaneously into contact with the article and the label will be squarely and securely affixed to the article without the application of pressure to the latter. On account of the construction enabling the present mechanism to apply labels to articles in the above described manner, the mechanism is particularly adapted for labeling relatively soft or plastic articles such for example as yeast cakes without danger of altering the shape of the article or otherwise injuring it by the application of an excess of pressure at one side thereof as a result of an inaccurately levelled label affixing plate.

To insure that the label affixing plate 58 will be exactly horizontal when in label affixing position, the plate is secured to the arm 62 with provision for tilting or angular adjustment relatively thereto. To this end, the plate 58 is supported in spaced relation to the end of the arm 62 by a screw 98 which extends centrally through the plate and is threaded into the arm, the screw being provided with a bevelled head which is countersunk within the plate. The plate 58 rests upon the head of the screw 98, the upper face of the plate engaging at one end

with a lug 100 on the drum and at the opposite end with the squared head of a bolt 102, the shank of which is also threaded into the end of the arm 62. With this arrangement, by turning the screw 98 and the bolt 102 the plate may be tilted, about the lug 100 as a fulcrum, until the proper angular relation between the plate and the arm is attained. The plate 58 may then be locked in adjusted position by unscrewing the bolt 102 until its head engages the plate and binds the latter against the head of the screw 98 and the lug 100.

The nipper 60, which cooperates with the plate 58 to seize and transfer the labels, comprises a resilient label engaging finger carried by an unyielding nipper arm 106, the latter being pivoted at a point 108 intermediate its ends, to the arm 62. The free extremity of the resilient finger 60 is bent inwardly as shown, to cooperate with the adjacent bevelled end of the plate 58. Thus the bevelled end of the plate 58 constitutes the fixed jaw of the label transferring nipper whereas the finger 60 constitutes the movable jaw thereof. The upper end of the nipper arm 106 is pivotally connected at 106' to a link 110 which is pivotally connected at 111 to the lower arm of an elbow lever 112 which is pivoted at 114 to the arm 62. The link 110 and the lower arm of the lever 112 are arranged in the form of a toggle whereby a downward swinging movement of the lever 112 will move the pivot 111 to a point below a center line extending between the pivotal points 106' and 114 and will hold the movable nipper jaw or finger 60 against the fixed nipper jaw or bevelled portion of the plate 58, while an upward movement of the lever 112 will cause the nipper jaws to separate to release the label held between them. A spring 116 is seated at one end in a socket in the arm 62 and arranged with its opposite end bearing against the lower portion of the nipper arm 106 to hold the nipper open and the lever 112 in its uppermost position. The open or inoperative position of the nipper finger is determined by engagement of the upper side of the link 110 with a stop lug 118 on the arm 62. A similar stop lug 120 is adapted to engage the under side of the link 110 to limit the downward movement of the lever 112 and thus enable the nipper to be maintained closed with the resilient nipper finger 60 under sufficient tension to firmly grip the label.

To open and close the label transferring nipper 60, the lever 112 is adapted to be actuated by means of the rocker member 72 already mentioned. To this end the rocker member 72 is rigidly secured to the front end of a rock shaft 120 which is journaled within the sleeve 68. The rear end of the rock shaft 120 projects beyond the bearing

sleeve 68 and has fixed thereto a depending arm 122 carrying a cam roll 124 which rides in a groove in a cam disk 126 that is secured to the main shaft 78. The rocker member 5 72 is provided with two oppositely curved arms 128 and 130, the free extremity of the arm 128 being adapted to actuate the lever 112 to close the nipper 60 and the free extremity of the arm 130 being adapted to 10 actuate the lever 112 to open the nipper 60. The arms 128 and 130 of the rocker member are widely separated, as shown, so that while said arms are in the path of the lever 112, as the latter is moved bodily with the 15 label applying device 50, said device will be permitted to move to the limit of its travel in either direction without causing the lever 112 to be actuated so that the nipper will be either opened or closed. As the label applying device 50 reaches the limit of its upward travel, the nipper is open, the movable nipper jaw 60 being positioned below the free end of the label strip which projects slightly beyond the holding device 30, while the fixed 20 nipper jaw is located just above said end of the strip, as shown in Fig. 2. The shaft 120 is then rocked by the action of the cam 126 so as to swing the rocker arm 128 downwardly, thus rocking the lever 112 downwardly until the link 110 is brought into 25 engagement with the stop lug 120. The nipper consequently is closed to seize the end of the label strip. The label applying device 50 is then moved downwardly, first 30 drawing the label strip through the holding device 30 and then, after a label has been severed from the strip, carrying the severed label therewith. As the label affixing device 35 reaches the limit of its downward travel, the shaft 120 is rocked by the action of the cam 126 so that the rocker arm 130 swings the lever 112 upwardly, bringing the link 110 into engagement with the stop lug 118 and opening the nipper to release the label 40 held thereby, as the latter is being affixed to the article 18. As shown, the free end of the rocker member 130 is forked so that it will not interfere with the link 110 and the upper portion of the nipper arm 106 45 upon the upward travel of the label applying device 50. In order that the lever 112 shall be actuated by the forked arm 130 said lever is provided with axially aligned 50 rollers 132 (Fig. 3) which project from opposite sides of the lever to be engaged by the forked extremity of the rocker arm 130. 55 The label severing knife 52 is carried by a rod 134 which extends at right angles to a cam lever 135, the rod 134 being adjustably secured in a split socket at one end of the lever by means of a bolt 136. The lever 135 is fulcrumed at 138 upon the frame 8 and carries at its upper end a cam roll 140. The roll 140 is held against the periphery of the disk 76 by the action of a spring 142, the

latter being fastened at one end to the cam lever 136 and at the opposite end to the frame 8. The periphery of the disk 76 is provided with a cam face 144 which is constructed and arranged to effect the upward 70 swinging of the knife 52 just before a row of perforations 38 in the strip 26 passes above the knife. The upper or cutting edge of the knife 52 is serrated, as shown at 146 75 in Fig. 6, the teeth being spaced to engage within the perforations in the label strip.

As the knife 52 is swung upwardly it engages the lower side of the label strip, lifting the strip slightly to put it under tension so that when the first row of perforations reaches the knife the many points in the serrated edge of the knife 146 will enter the perforations and, by reason of their wedge like character, will readily sever the connecting portions between the 80 perforations. If, for any reason, however, the severing does not take place, upon the upward movement of the knife 52, or if the severing is only partially accomplished, the points in the cutting edge of the knife 85 will hold the strip while the nipper 60 pulls the leading portion thereof away from the rest of the strip. Thus, in any event, the severing is positively insured. It will be 90 seen that by loosening the bolt 135 the rod 134 may be turned in its split socket in the lever 136 and the angularity of the knife 52 relatively to said lever readily varied. Thus the cutting edge of the knife 52 may 95 be adjusted to facilitate its severing action. The knife should be so adjusted that the severing will take place at such a distance from the holding device 30 as to insure the projection beyond said device, after the 100 severing operation, of a sufficient length of label strip to be readily seized by the nipper upon the next upward movement of the latter.

The label moistening device includes, in addition to the glue roll 54 already mentioned, a glue tank 146 of the shape best shown in Figs. 1 and 3, which may be detachably secured in any suitable manner to the frame 8 or otherwise removably supported as may be found desirable. The glue roll 54 protrudes through an aperture in an inclined wall 148 at one end of the tank, the trunnions of the roll being journaled in a well-known manner to the side 110 walls of the tank. To facilitate the application of the glue to the label the glue roll is positively driven so that the portion 115 of the roll which contacts with the label will travel in the same direction and at the same speed as that of the label. To this end a driving shaft 150 is journaled in a bearing in the frame 8, in axial alignment with the axis of the glue roll, and is detachably connected to drive the roll by means 120 of a horizontal pin 152 (Fig. 1) projecting 125 from the side of the tank. The tank 146 is 130

from the side of a collar fixed to the shaft 150 and arranged to engage a radial pin 154 in the adjacent trunnion of the glue roll. The shaft 150 is driven from the main shaft 78 through a train of gearing comprising the gears 156 and 158 on the shafts 78 and 150, respectively, and an intermediate idler pinion 160. Obviously, if gummed labels are to be employed, the described adhesive applying device would be replaced by a suitable moistening device.

The operation of the mechanism has been explained in connection with the description given above of the construction and arrangement of its various parts. By virtue of the described construction and arrangement of parts the labels are handled and applied in a thoroughly practical and efficient manner and the labeling operation may be carried on at an unusually high rate of speed. The labels are coated with adhesive during their transfer from the supply to the article to be labeled without retarding the transfer operation. Furthermore, the labels are applied to the articles without pressure and in a uniform manner whereby there is no tendency to compress or distort soft or plastic articles.

While it is preferred to employ the specific construction and arrangement of parts shown and described, it will be understood that this construction and arrangement is not essential since it may be variously modified without departing from the broader features of the invention.

I claim:

1. In a mechanism of the character described, the combination with a rotatable adhesive applying roll, of a flat label affixing plate for supporting a label and carrying it into engagement with the roll to receive an adhesive coating, an oscillatory carrier upon which the plate is mounted with provision for movement relatively thereto, and means for moving the plate relatively to the carrier during a portion of the oscillatory movement of the latter to facilitate the application of adhesive to the label.

2. In a mechanism of the character described, the combination with a rotatable adhesive applying roll, of a flat label affixing plate for supporting a label and carrying it into engagement with the roll to receive an adhesive coating, an oscillatory carrier upon which the plate is mounted with provision for movement relatively thereto, and means rendered operative by movement of the carrier for moving the plate relatively to the carrier during a portion of the oscillatory movement of the latter to cause substantially the entire exposed surface of the label to engage the roll.

3. In a mechanism of the character described, the combination with a rotatable adhesive applying roll, of a flat label affix-

ing plate for supporting a label and carrying it into engagement with the roll to receive an adhesive coating, an oscillatory carrier upon which the plate is mounted with provision for movement relatively thereto, and means for moving the plate relatively to the carrier during a portion of the oscillatory movement of the latter to bring said label into contact with the roll along a line extending transversely across the forward end portion of the label and to cause said line of contact to progress rearwardly over the surface of the label.

4. In a mechanism of the character described, the combination with a rotatable adhesive applying roll, of a flat label affixing plate for supporting a label and carrying it into engagement with the roll to receive an adhesive coating, an arm upon which said plate is mounted, an oscillatory carrier to which said arm is pivotally connected and a cam for controlling the movement of said arm as said carrier oscillates, the cam being constructed and arranged to cause substantially the entire exposed surface of the label to engage the roll.

5. In a mechanism of the character described, the combination with a rotatable adhesive applying roll, of a flat label affixing plate for supporting a label and carrying it into engagement with the roll to receive an adhesive coating, an arm upon which said plate is adjustably mounted, an oscillatory carrier to which said arm is pivotally connected, means for controlling the movement of said arm as said carrier oscillates to cause substantially the entire exposed surface of the label carried by said plate to be engaged by the roll, and adjusting means for varying the angular relation of said plate to said arm.

6. In a mechanism of the character described, the combination with a rotatable adhesive applying roll, of a flat label affixing plate for supporting a label and carrying it into engagement with the roll to receive an adhesive coating, an arm upon which said plate is adjustably mounted, an oscillatory carrier to which said arm is pivotally connected, a cam roller carried by said arm, a stationary cam face for controlling the movement of the arm as the carrier oscillates the cam being constructed and arranged to tilt the arm relatively to the carrier so as to cause substantially the entire exposed surface of a label carried by the plate to be engaged by the roll, and a spring for holding said cam roller in operative engagement with said cam face.

7. In a mechanism of the character described, the combination with a rotatable adhesive applying roll, of a flat label affixing plate for supporting a label and carrying it into engagement with the roll to receive an adhesive coating, an oscillatory

carrier upon which the plate is mounted with provision for movement relatively thereto, means for moving the plate relatively to the carrier during a portion of the oscillatory movement of the latter to enable substantially the entire exposed surface of the label carried by said plate to be engaged by the roll, and means for positively rotating the roll at a surface speed equal to 10 the rate of travel of the label and in the same direction.

8. In a mechanism of the character described, the combination with a rotatable adhesive applying roll of a flat label affixing plate for supporting a label and carrying it into engagement with the roll to receive an adhesive coating, an oscillatory carrier upon which the plate is mounted with provision for movement relatively thereto, and means for moving the plate relatively to the carrier during a portion of the oscillatory movement of the latter to cause substantially the entire exposed surface of the label carried by said plate to be engaged 20 by the roll, said means being constructed and arranged to maintain the plate substantially tangent to the roll throughout its period of engagement therewith.

9. In a label applying mechanism, the combination with a support for an article to be operated upon, of means removed from said support for receiving a supply of labels, an oscillatory member pivoted above the article upon said support, a carrier mounted 30 upon said member with provision for angular movement relatively thereto, means including a label affixing plate carried by said member for removing a label from the supply and affixing it to an article upon said support, means for actuating said member to effect the transfer of the label, and means including a cam for engaging said carrier during said transfer for varying the angular relation of the carrier to said member to cause the label carried by said plate to be 40 applied to the article by a movement of the former substantially at right angles to the upper face of the latter.

10. In a label applying mechanism, the combination with a support for an article to be operated upon, of means removed from said support for receiving a supply of labels, a roll between said label supply and said support for applying an adhesive coating to 50 the labels, and means for removing a label from the supply, transferring it past said roll to a position above said support and affixing it to an article resting upon said support; said last named means comprising an oscillatory carrier pivoted above the article upon said support, a label seizing and affixing device mounted upon said carrier, and means for actuating the carrier to effect the transfer of the label, said means being 60 constructed and arranged to accelerate

the movement of the carrier during the advance stroke thereof.

11. In a label applying mechanism, the combination with a support for an article to be operated upon, of means removed from 70 said support for receiving a supply of labels, a roll between said label supply and said support for applying an adhesive coating to the labels, and means for removing a label from the supply, transferring it past said roll to a position above said support and affixing it to an article resting upon said support; said last named means comprising an oscillatory carrier pivoted above the article upon said support, a label seizing and affixing device 80 upon said carrier, a radial guideway in said carrier, and a crank pin movable in said guideway and arranged to effect the advance of said carrier while moving through that half of its orbit which is nearer the 85 axis of oscillation of the carrier.

12. In a mechanism of the character described, means for supporting the leading portion of a strip of labels, a yielding presser member cooperating with said supporting means, to frictionally hold said portion of the strip with its end exposed for grasping, a label applying device for grasping said end of the strip, drawing a portion thereof through said holding means and affixing it to an article at a point removed therefrom, means operative after a portion of said strip of predetermined length has been drawn through said holding means to sever said portion from the rest of the strip, and adjustable means associated with the holding device for engaging edges of the strip as the latter is drawn through said device to position the leading end of the strip transversely relatively to the label applying 95 device.

13. In a mechanism of the character described, a support for an article to be operated upon, means removed from said support for holding a supply of labels, a label affixing plate, a relatively movable nipper for cooperating with said plate to seize and hold a label, means for moving said plate and nipper bodily between said label supply and said support to transfer a label 100 from said supply to a position above said article and to affix it thereto, and means for actuating said nipper to seize a label at said supply by pressing a portion of the label against said plate and to release the 105 label as it is affixed to the article.

14. In a mechanism of the character described, a support for an article to be operated upon, means removed from said support for holding a supply of labels, a plate adapted to engage a label for the purpose of affixing the label to an article, a face adjacent one edge of said plate and offset from the plane of the label engaging side thereof, a nipper movable relatively to said plate 115

- for cooperating with said face to seize and hold a label, means for moving said plate and nipper bodily to remove a label from said supply and affix the label to an article 5 upon said support, and means for actuating said nipper to seize a label at said supply by pressing a portion of the label against said face and to release the label as it is affixed to the article.
- 10 15. The combination with means for intermittently feeding articles into position to receive a label and for supporting the articles during the label applying operation, of means removed from the path of 70 said articles for supporting a supply of labels, a plate for affixing a label carried thereby to an article, a nipper for cooperating with said plate to seize and carry a label, an oscillatory carrier for said plate and nipper adapted to move them back and forth between the label supply and the path of said articles, means for closing the nipper to grip a label from the supply between said nipper and said plate and for opening 75 the nipper to release the label as it is affixed to an article, and means for modifying the angular relation of said plate to said carrier during the oscillation of the latter to cause substantially all portions in the 80 exposed surface of the label carried by said plate to be brought simultaneously into contact with the article to which the label is to be applied by a movement of the label substantially at right angles to the upper 85 face of the article.
- 15 16. The combination with means for intermittently feeding articles into position to receive a label and for supporting the articles during the label applying operation, of means removed from the path of said 90 articles for supporting a supply of labels, a plate for affixing a label carried thereby to an article, a nipper for cooperating with said plate to seize and carry a label, an oscillatory carrier for said plate and nipper adapted to move them back and forth between the label supply and the path of said articles, means for closing the nipper upon 95 a label from the supply and for opening the nipper to release the label as it is affixed to an article, means including a roll in the path of movement of said plate for applying an adhesive coating to a label carried by the plate, and means for modifying the angular relation of the plate to said carrier during the oscillation of the latter to cause a line of contact between said label and roll to progress rearwardly over the surface 100 of the label.
- 20 17. The combination with means for intermittently feeding articles into position to receive a label and for supporting the articles during the label applying operation, of means removed from the path of said 105 articles for supporting a supply of labels, a carrier adapted to oscillate between the label supply and the path of said articles and adapted to bring said plate into position to affix a label to an article, means including a rocker member having spaced arms for actuating the nipper at opposite ends of the course of travel of the latter, and means acting in timed relation with 110 said carrier for rocking said plate in one direction to close the nipper and in the opposite direction to open the nipper.
- 25 18. The combination with means for intermittently feeding articles into position to receive a label and for supporting the articles during the label applying operation, of means removed from the path of said articles for supporting a supply of labels, a carrier adapted to oscillate between the label supply and the path of said articles, a label affixing device and a nipper mounted on said carrier, the nipper adapted to cooperate with said device to seize a label, means including 115 a lever mounted on the carrier for actuating the nipper, a rocker member having spaced arms between which said lever moves as the carrier oscillates, and means for rocking said member to swing said lever in one direction to close the nipper upon a label at the source of supply and for rocking said member to swing said lever in the opposite direction to open the nipper to release the label as the latter is affixed to the article.
- 30 19. The combination with means for intermittently feeding articles into position to receive a label and for supporting the articles during the label applying operation, of means removed from the path of said 120 articles for supporting a supply of labels, a carrier adapted to oscillate between the label supply and the path of said articles, an arm pivoted upon said carrier, a label-affixing plate carried by said arm, a nipper comprising a resilient finger for cooperating with said plate to seize and hold a label, an unyielding nipper support pivotally mounted upon said arm, means for actuating said nipper comprising toggle links connected 125 one to said arm and the other to said nipper support, means for limiting the movement of the toggle links in one direction to maintain the nipper finger in cooperative engagement with said plate, and means for swinging the toggle links away from said limit means to break the toggle to open said nipper and thereby to release the label.
- 35 20. The combination with means for intermittently feeding articles into position to receive a label and for supporting the articles during the label applying operation, of means removed from the path of said 130 articles for supporting a supply of labels, a carrier adapted to oscillate between the label supply and the path of said articles, an

- arm pivoted upon said carrier, a label affixing plate carried by said arm, a nipper comprising a resilient finger for cooperating with said plate to seize and hold a label, an unyielding nipper support pivotally mounted upon said arm, connections between said nipper support and said arm adapted to actuate said nipper arranged to hold the nipper in open and closed positions.
- 10 21. The combination with means for intermittently feeding articles in position to receive a label and for supporting the articles during the label applying operation, of means removed from the path of said articles for supporting a supply of labels,

a carrier adapted to oscillate between the label supply and the path of said articles, a member movable on said carrier, a label affixing plate on said member, a label engaging nipper cooperating with said member for holding a label, a movable nipper support pivotally mounted on said member, connections between said nipper support and member adapted to move said nipper relatively to said plate and arranged to hold 25 said nipper away or against said plate.

In testimony whereof I have affixed my signature.

ELMER L. SMITH.
